UNITED STATES PATENT OFFICE.

WILLIAM SPARKS, OF JACKSON, MICHIGAN.

DESIGN FOR A ROTARY FAN.

43,510.

Specification for Design.

Patented Feb. 4, 1913.

Application filed October 4, 1911. Serial No. 652,857. Term of patent 14 years.

To all whom it may concern:

Be it known that I, WILLIAM SPARKS, a citizen of the United States, residing at Jackson, in the county of Jackson and State of Michigan, have invented a new, original, and ornamental Design for Rotary Fans, of which the following is a specification, reference being had to the accompanying drawing, forming part thereof.

Figure 1 is a face view and Fig. 2 is a

side elevation of a rotary fan showing my new design.

I claim:

The ornamental design for a rotary fan, as shown.

WM. SPARKS.

Witnesses:

H. BURCHARD,

F. G. WHITTINGTON.
